CLAIM

The ornamental design for an apparatus for manipulating hollow organs, as shown and described.

DESCRIPTION

FIG. 1 is a first side view of a first embodiment of an apparatus for manipulating hollow organs, showing my new design;

FIG. 2 is a second side view of the first embodiment of the apparatus for manipulating hollow organs shown in FIG. 1; FIG. 3 is a top view of the first embodiment of the apparatus for manipulating hollow organs shown in FIG. 1;

FIG. 4 is a bottom view of the first embodiment of the apparatus for manipulating hollow organs shown in FIG. 1; FIG. 5 is a front view of the first embodiment of the apparatus for manipulating hollow organs shown in FIG. 1;

FIG. 6 is a rear view of the first embodiment of the apparatus for manipulating hollow organs shown in FIG. 1;

FIG. 7 is a frontal perspective view of the first embodiment of the apparatus for manipulating hollow organs shown in FIGS. 1-6;

FIG. 8 is a first side view of a second embodiment of an apparatus for manipulating hollow organs according to my new design;

FIG. 9 is a second side view of the second embodiment of the apparatus for manipulating hollow organs shown in FIG. 8;

FIG. 10 is a top view of the second embodiment of the apparatus for manipulating hollow organs shown in FIG. 8; FIG. 11 is a bottom view of the second embodiment of the apparatus for manipulating hollow organs shown in FIG. 8; FIG. 12 is a front view of the second embodiment of the apparatus for manipulating hollow organs shown in FIG. 8; FIG. 13 is a rear view of the second embodiment of the apparatus for manipulating hollow organs shown in FIG. 8; and,

FIG. 14 is a frontal perspective view of the second embodiment of the apparatus for manipulating hollow organs shown in FIGS. 8-13.

Broken lines showing a remainder of the apparatus are directed to environment, and are for illustrative purposes only; the broken lines form no part of the claimed design.

1 Claim, 4 Drawing Sheets
